COMBINED LECTERN AND CABINET

Milton J. Miller, Broc W. Henrikson, and Chester J. Barecki, Grand Rapids, Mich., assignors to American Seating Company, Grand Rapids, Mich., a corporation of Delaware

Filed Dec. 22, 1966, Ser. No. 5,160

Term of patent 14 years

(Cl. D33—10)

FIG. 1

FIG. 2

We claim:

The ornamental design for a combined lectern and cabinet, as shown.
